UNITED STATES PATENT OFFICE.

HENRY G. WATSON, OF DETROIT, MICHIGAN, ASSIGNOR TO MURPHY IRON WORKS, OF DETROIT, MICHIGAN, A CORPORATION OF MICHIGAN.

CLINKER-BAR.

1,278,405.

Specification of Letters Patent. Patented Sept. 10, 1918.

Application filed January 16, 1914. Serial No. 812,482.

To all whom it may concern:

Be it known that I, HENRY G. WATSON, a citizen of the United States of America, residing at Detroit, in the county of Wayne 5 and State of Michigan, have invented certain new and useful Improvements in Clinker-Bars, of which the following is a specification, reference being had therein to the accompanying drawing.

10 In automatic stokers and other furnaces of the type in which inclined, movable grate bars are employed, a rotatable clinker bar is usually mounted at the lower ends of said bars to grind or crush the clinkers and gradually feed out the ash. It was found that the extreme heat to which these clinker bars were subjected caused them to warp, crack and become partially disintegrated in a short time, and to obviate these difficulties 15 clinker bars have been made up of a plurality of sections strung upon and secured to suitable shafts. In practice, it is however, necessary to make the shaft very large and heavy so that it will not be twisted and 20 broken under the heavy strain of rotating the clinker bar to crush clinkers, and further, it is also necessary to form the shaft and sections or otherwise connect them so that the sections can not turn on the shaft. The 25 construction is therefore necessarily cumbersome and expensive to manufacture, and difficulty is experienced in assembling.

The object of this invention is to provide a sectional clinker bar construction which 30 embodies comparative lightness and cheapness of manufacture with great strength and rigidity obviating all liability of breakage of the shaft and giving a construction in which the sections may be quickly and easily 35 removed for replacement or repair. With these and other ends in view, the invention consists in the matters hereinafter set forth and more particularly pointed out in the appended claims, reference being had to the accompanying drawing in which—

Figure 1 is a longitudinal section through a portion of a furnace illustrating a clinker bar embodying the invention in operative position therein with parts of the bar broken 40 away and in section to show the construction.

Fig. 2 is a transverse vertical* section through the same; and

Fig. 3 is a perspective view of parts of the 55 clinker bar detached.

As shown in the drawing 1, 1 represent two series of inclined grate bars each comprising stationary bars 2 alternating with movable bars 3, the stationary bars being supported at their lower ends upon the upper edges of the side plates 4 of a suitable grate bearer 5 and the movable bars being supported and actuated by shafts 6 each having a laterally extending rib 7 to engage notches 8 in said bars 3 and raise and lower 60 the bars as the shafts are turned, all being supported at their lower ends upon the upper edges of the side plates 4 of a suitable grate bearer 5 and the movable bars being supported and actuated by shafts 6 each having a laterally extending rib 7 to engage notches 8 in said bars 3 and raise and lower 65 the bars as the shafts are turned, all being constructed and arranged in an old and well known manner.

The grate bearer 5 is provided with a 70 series of transverse bearing members 9 forming bearings for a rotatable clinker bar 10 comprising a tubular shaft 11 upon which are sleeved a number of sections 12 provided with a plurality of teeth or studs 13. These 75 sections are of such a length that they extend from near one bearing to a point adjacent to the next bearing and sleeved upon the shaft between the toothed sections are short plain bearing sections 14 adapted to turn in the bearings 9. At each end, each 80 of the sections 12 and 14 are formed with notches 15 in opposite sides, said notches forming between them longitudinally extending lugs 16 to engage the notches in the 85 abutting end of the next section. The sections are thus interlocked and upon the forward end of the shaft 11 is a sleeve 17 which projects through a suitable bearing opening provided therefor in the furnace front 18. The outer end of the sleeve is substantially 90 rectangular in cross-sectional outline but it may be formed in any suitable manner to be engaged by means (not shown) for turning the clinker bar and its inner end is provided with lugs and notches corresponding 95 to the lugs and notches on the sections to interlock with the adjacent section. Pins 19 extending through openings in the shaft 11 in engagement with the outer ends of the sleeve 17 and the rear end of the rear bearing section 14, hold the shaft against longitudinal movement through the sections and

100

clamp the sections together against separation, and an annular rib 20 on the sleeve engaging the bearing in the furnace front and a like rib 21 on the rear bearing section 5 prevents longitudinal movement of the clinker bar in its bearings in the grate bearer.

As the power is applied to the sleeve 17 which is interlocked with the adjacent end 10 of the first of the interlocked sections, the twisting strain of turning the clinker bar is taken by the sections direct and the shaft 11 simply forms a support for the sections. The shaft may therefore be made comparatively light and tubular (as shown) if desired, so that air or steam may be circulated therethrough to assist in keeping the bar cool and prevent the same from being burned or warped by the excessive heat. The arrangement 20 of interlocking sections also permits of the use of a length of stock tubing or shafting and it is unnecessary to form or machine the shaft, thus greatly lessening the cost of manufacture as the sections may be 25 readily cast with their interlocking lugs and simply strung upon the shaft.

Obviously, changes may be made in the construction and arrangement of parts without departing from the spirit of my invention and I do not therefore limit myself to the form or arrangement shown.

Having thus fully described my invention what I claim is:—

1. A rotatable clinker bar comprising a series 35 of tubular sections having formed ends adapted to interlock, a shaft extending through and fitting within said sections to aline the same and turn therewith and to form a strengthening and supporting member therefor, and means for applying power to one of said sections to turn the bar.

2. A rotatable clinker bar comprising a shaft, a series of sections formed with external teeth, a plurality of plain bearing sections, all of said sections being sleeved upon 45 said shaft with the plain sections interposed between the toothed sections and all of said sections being formed with longitudinal lugs at each end, the lugs of one section being 50 adapted to interlock with those of the adjacent sections, and means for applying power to one of the sections.

3. A rotatable clinker bar comprising a plain shaft, a series of toothed sections, a series 55 of plain sections alternating with the toothed sections, lugs on each end of each section to interlock with the lugs on the adjacent sections, all of said sections being sleeved upon said shaft in interlocked relation, and a sleeve on said shaft at one end thereof, lugs at one end to interlock with the lugs on the adjacent section and formed at its opposite end for the application of power thereto.

4. In a clinker bar, the combination of the

plurality of tubular sections having end driving engagement, one with another, a member extending through said sections to aline and support the same, means for preventing the separation of said sections upon 70 said member, and means for applying power to one of the sections to turn all of them.

5. In a clinker bar for furnaces, the combination with a tubular rotatable driver member having a driving face on the inner 75 end thereof and means on its outer end for rotating the member, of a plurality of hollow and longitudinally separable grinder members having one through another a driving engagement with the driver member, 80 and a non-driving guide member extending through the grinder members for holding these members in working alinement, and having a passage for a current of air.

6. In a clinker grinder for furnaces, the 85 combination with a tubular rotatable driver member having a driving face on the inner end thereof and provided with means for rotating the same, of a plurality of hollow and longitudinally separable grinder members 90 having one through another a driving engagement with the driver member, and a guide member arranged for removal independently of the removal of the driver member and extending through the grinder members 95 for holding these members in working alinement, and having a passage for a current of air.

7. In a clinker grinder for furnaces, the combination with a tubular rotatable driver 100 member having a driving face on the inner end thereof and means at its outer end for rotating the driver member, of a plurality of hollow and longitudinally separable interlocking grinder members having one through 105 another a driving engagement with the driver member, a guide member removably supported within and extending through the grinder members for holding these members in working alinement, and having a longitudinal passage for a current of air, and means in operative connection with said guide member for clamping together the grinder members by the aid of said guide member.

8. In a clinker-grinder for furnaces, the combination with a tubular rotatable driver-member having a driving face on the inner end thereof, of actuating means for rotating the driver-member, a plurality of hollow and longitudinally separable grinder-members having one through another a driving engagement with the driver-member, and a non-driving guide bar extending through the grinder members for holding these members 120 in working alinement, and having a passage for a current of air, substantially as described.

9. In a clinker-grinder for furnaces, the combination with a tubular rotatable driver- 125

member having a driving face on the inner end thereof, of actuating means for rotating the driver-member, a plurality of hollow and longitudinally separable grinder-members having one through another a driving engagement with the driver-member, and a guide bar arranged for removal independently of the removal of the driver-member and extending through the grinder-members

for holding these members in working alignment, and having a passage for a current of air, substantially as described.

In testimony whereof I affix my signature in presence of two witnesses.

HENRY G. WATSON.
